INTERDENTAL PROPHYLACTIC MOUTHWASH DISPENSER

Garrison Trupp, 4600 York Road 21212, and Bernard Trupp, 3900 N. Charles 21218, both of Baltimore Md.

Filed Feb. 15, 1967, Ser. No. 5,832

Term of patent 14 years

(Cl. D24—1)

FIG. 1

FIG. 2

FIG. 3

FIG. 4

FIG. 5

FIG. 6 FIG. 7

FIG. 8

FIG. 1 is a front elevation of an interdental prophylactic mouthwash dispenser, showing our new design;

FIG. 2 is a side elevational view;

FIG. 3 is a rear elevational view;

FIG. 4 is a top plan view;

FIG. 5 is a top plan view thereof; and

FIGS. 6, 7 and 8 are side elevations showing modified embodiments of the dispensing tip shown in FIG. 1. The side not shown is a mirror image of FIG. 2.

We claim:

The ornamental design for an interdental prophylactic mouthwash dispenser, as shown and described.
